UNITED STATES PATENT OFFICE

SOLOMON M. SAGER, OF GLENCOE, ILLINOIS

ELECTRIC ADVERTISING AND DEMONSTRATING MACHINE

Application filed June 29, 1931. Serial No. 547,548.

This invention relates to an improved type of electric advertising machine and more particularly to a fountain pen demonstrating machine which acts mechanically to alternately fill and empty a plunger type transparent barrel fountain pen with a fluid which is adapted to be drawn from a filling cup into the fountain pen barrel after which the filled fountain pen is mechanically conducted into 5 a position over a discharge container in which position the fountain pen plunger is actuated by automatic means for causing the charge of fluid within the fountain pen barrel to be discharged into the receiving container and permitting the emptied fountain 10 pen to be carried back into a filling position to permit the cycle of operation to be repeated in the presence of an electrically illuminated advertising and explanatory 15 mechanism which is operated in synchronized relation from the machine for the purpose of explaining the various steps in the demonstration by either visible or audible means. 20 It is an object of this invention to provide 25 an improved type of demonstrating machine which will automatically act to operate a transparent barrel plunger type fountain pen to clearly and graphically demonstrate the various successive steps required for filling 30 and emptying the fountain pen barrel. It is also an object of this invention to provide 35 a fountain pen demonstrating machine which is adapted to be carried back and forth between a filling container and a discharge 40 container into the fields of operation of automatic mechanisms operable to cause the extended plunger filling mechanism to be depressed to cause filling of the fountain pen barrel in one extreme position of travel of 45 the fountain pen and furthermore cause an outward movement of the plunger filling mechanism in the opposite extreme position of travel of the fountain pen to cause the fluid contents of the fountain pen barrel to be discharged into a receiving container. 50 It is a further object of this invention to provide an electric advertising machine in the form of a demonstrator which will automatically act to carry a transparent barrel plunger type fountain pen through a pre-

determined path between a filling container and a discharge container to cause the fountain pen plunger, when the fountain pen is in its extreme positions of travel, to be automatically operated by a control mechanism 55 to cause filling of the transparent barrel when the fountain pen is over the filling container and furthermore causing discharge of the contents of the fountain pen barrel when the fountain pen is over the discharge container, 60 said machine being provided with a mechanism also operable by the control mechanism to describe the various steps and advantages of the fountain pen during the demonstration. 65

It is furthermore an object of this invention to provide an electric advertising machine and demonstrator which will mechanically operate a transparent barrel plunger type fountain pen to cause the fountain pen 70 to take in a charge of fluid and then discharge the fluid to completely empty the fountain pen barrel by means of plunger actuating members actuated by a common control which also governs the operation of visible or audible means for explaining and 75 describing the various features, advantages and the operation of the fountain pen which is being mechanically demonstrated by the machine. 80

Another object of the invention is to provide a fountain pen demonstrating machine including a fountain pen carrier for holding and carrying a transparent barrel plunger type fountain pen with the plunger head exposed to permit the plunger to be reciprocated in the fountain pen barrel at predetermined times to cause a charge of fluid to be drawn into the barrel from a filling container and adapted in another position to cause the charge of liquid to be discharged from the fountain pen barrel into a receiving container which is connected with the filling container to permit liquid discharged thereinto to be automatically returned to the filling container, 85 said filling container having connected therewith a liquid supply or replenishing container or tank for the purpose of maintaining an adequate supply of liquid in the filling container to compensate for 90 95 100

evaporation of the liquid used for demonstrating purposes.

It is an important object of this invention to provide an improved type of electric advertising and demonstrating machine including a casing having a display front having liquid containers or cups to the front thereof and also disclosing a transparent barrel plunger type fountain pen with the head cap 10 removed to disclose the head of the filling plunger to permit the filling plunger to be reciprocated at predetermined intervals by actuating members operated from the interior of the machine casing to cause the 15 fountain pen to draw in a charge of liquid from one of the containers and then discharge the charge of liquid into the other container with the various steps in the operation and demonstration adapted to be described by 20 mechanical advertising means which are also operated from the machine, thereby providing an improved and simplified machine which will practically eliminate the human element and which will automatically operate 25 the fountain pen to fill and empty the same and at the same time set forth the various features and advantages of the particular fountain pen or article which is being demonstrated.

30 Other and further important objects of this invention will be apparent from the disclosures in the specification and the accompanying drawings.

35 The invention (in a preferred form) is illustrated in the drawings and hereinafter more fully described.

On the drawings:

40 Figure 1 is a front elevation of an improved electric advertising and demonstrating machine embodying the principles of this invention and disclosing a transparent barrel plunger type fountain pen held in a filled position and indicating the travel of the fountain pen in dotted lines.

45 Figure 2 is an enlarged fragmentary front view of the machine mechanism with parts shown in section and with the casing omitted.

50 Figure 3 is a fragmentary elevational side view of the machine taken on line III-III of Figure 2 with parts of the casing omitted and with the driving gear housing in section.

55 Figure 4 is a reduced fragmentary front view of the machine mechanism illustrating the fountain pen in full lines with the barrel empty and with the filling plunger extended and illustrating in dotted lines the position of the plunger operating mechanism for causing the fountain pen barrel to be filled with 60 a charge of ink when the feed plunger is depressed. The view furthermore illustrates the movement of the fountain pen from a filling position toward a discharge position with the pen illustrated in dotted lines in 65 an intermediate position to indicate that the

pen is rotated during its travel from a filling position to a discharge position.

70 Figure 5 is a view similar to Figure 4 illustrating the filled fountain pen in full lines in its discharge position and illustrating in dotted lines the operation of the plunger actuating control mechanisms which cause the charge of liquid in the fountain pen to be discharged into the receiving container.

75 Figure 6 is an enlarged fragmentary detail section of the upper portion of the liquid supply unit taken on line VI-VI of Figure 2.

80 Figure 7 is an enlarged fragmentary sectional view taken on line VII-VII of Figure 2 illustrating the details of the control mechanisms for governing the flow of liquid from the reserve tank to the filling container.

85 As shown on the drawings:

90 The improved electric advertising and demonstrating machine comprises a housing or casing 1 provided with a base plate or board 2. The casing is provided with a removable glass front 3 which may be removed through the top portion of the casing 1 by removing the upper frame strip 4. The back of the casing is closed by means of an ordinary hinged door which is not illustrated.

95 Mounted in the front portion of the casing 1 a short distance inwardly or in back of the glass front plate 3 is a display panel or board 5 having provided in the upper central portion thereof an advertising window or display opening 6. Provided substantially in the middle portion of the panel 5 is a 100 transversely positioned main arcuate or curved slot 7 which is slightly inclined as clearly illustrated in Figure 1. Provided in the panel 5 above the lower end of the main slot 7 is a vertically inclined auxiliary arcuate or curved slot 8. Also provided in the panel 5 above the upper end of the main slot 7 is a slightly inclined arcuate or curved auxiliary slot 9. Provided in the lower portion of the panel 5 are openings through 105 which pipes or tubes 10 and 11 project from the rear chamber of the housing into the space provided between the glass front 2 and the panel 5. The front end of the pipe 10 is 110 curved upwardly and supports a liquid supply or feed cup or container 12 the body portion of which is transparent so that the demonstrating liquid may be seen through the cup. The front end of the pipe 11 is also 115 bent upwardly and has supported thereon a discharge cup or container 13 the body portion of which is also transparent so that liquid discharged into the cup may be viewed through the walls of the cup. As clearly 120 illustrated in Figure 1 the discharge cup or container 13 is at a slightly higher elevation than the cup or container 12 so that liquid discharged into the discharge cup 13 is permitted to flow through the pipe 11 back to 125 the cup 12 by means of a return pipe or tube 130

14. Also connected with the pipe or tube 10 is a supply pipe or tube 15 the opposite end of which connects up with the bottom of a liquid supply chamber 16 provided in a chambered supporting base 17 which as clearly illustrated in Figure 7 is mounted upon a supporting bracket or frame 18 fastened in the rear chamber of the housing 1. The top plate of the base section 17 is provided with a central opening 19. The base section 17 is seated in an outer shell or casing 20 which rests upon the top of the tablet bracket or support 18 and projects upwardly above the top of the base section 17.

15 For the purpose of providing a reserve supply of demonstrating liquid a liquid supply bottle or tank 21 is provided and the neck of the bottle 21 is equipped with a cap 22. The top of the cap 22 is provided with an opening 20 in which a sleeve or collar 23 is secured. The inner end of the collar or sleeve 23 affords a valve seat at 24 (Figure 7) against which a valve 25 normally seats. The valve 25 is provided with a valve stem 26 which slidably projects through an opening in a cup or casing 27 which is secured on the inner side of the top plate of the cap 22 and projects into the neck of the bottle 21. The bottom plate of the cup 27 is provided with openings 28 to permit the liquid from the bottle to flow into the cup 27 when the reserve tank or bottle is inverted and positioned with the cap 22 thereof seated against the top plate of the supporting base section 17. Engaged around the valve stem 26 between the valve 25 and the end plate of the cup 27 is a coiled control spring 29 which acts to hold the valve 25 in closed position against the valve seat 24 so that liquid from the bottle 21 passing 35 into the cup 27 is prevented from flowing out of the bottle or tank. Rigidly secured in the base section 17 is an axially disposed pin or rod 30 provided with a disc head 31 on its upper end. The headed pin or rod 30 is so positioned that when the capped bottle 21 is inverted and seated upon the apertured top plate of the base section 17 the head 31 of the rod projects upwardly through the collar 23 and contacts the valve 25 causing 40 the same to be moved into the open position illustrated in Figure 7. With the valve 25 open it will be noted that liquid from the bottle 21 is adapted to flow through the openings 28 of the cup 27 and through the collar 23 into the chamber 16 of the base section 45 from which the liquid is adapted to flow through the outlet pipe 15 to replenish the supply of demonstrating liquid in the supply cup or container 12 to compensate for the loss 50 of the demonstrating liquid due to evaporation or other causes during the operation of the demonstrating machine. For the purpose of holding the reserve bottle or tank 21 in position tightly against the base section 55 17 a clamping plate or hood 31 is engaged

over the upturned bottom of the bottle 21. The hood or clamping plate 31 is provided with diametrically opposite projections or lugs 32 to removably receive the hooked ends 33 of a pair of retaining coiled springs 34. 70 The lower ends of the coiled springs 34 are shaped to provide hooks 35 which are engaged through openings provided in opposite sides of the tablet bracket or support 18. 75 The improved machine is intended for the purpose of advertising and demonstrating the operation of an improved fountain pen having a transparent barrel or body section 36 which is adapted to be filled and emptied by means of a plunger mechanism 37. In the showing of the fountain pen the closure cap for normally enclosing the projecting head end of the plunger mechanism 37 is omitted to expose the head end of the plunger mechanism to permit the same to be actuated by the demonstrating machine. The lower or writing end of the fountain pen is provided with a pen point 38 and with the necessary feed bar. The improved fountain pen is provided with the transparent barrel 36 to permit a charge 80 of writing fluid admitted into the barrel to be readily seen through the transparent barrel so that a person using one of the fountain pens can readily ascertain when it is necessary to refill the fountain pen. 85

90 For demonstrating purposes the fountain pen to be demonstrated is adapted to be removably held in position by means of a supporting device or carrier comprising a bar or bracket 39 having integrally formed at right angles intermediate the ends thereof an outwardly projecting stud or arm 40. Mounted on each end of the supporting bar 39 is an adjustable gripping clip or clamping member 41 controlled by clamping screws 42 by means of which an adjustable portion of the clip 41 may be adjusted with respect to a stationary portion of the clip. The upper gripping clip 41 is adapted to be engaged around a boss provided on the upper end of the fountain pen barrel while the lower gripping clip is adapted to be clamped around the tapered section of the fountain pen barrel. The fountain pen is adapted to be secured in position on the holding bracket and said bracket is adapted in turn to be removably engaged in position by directing the supporting arm 40 through the main slot 7 of the demonstrating panel 5 between a pair of oppositely positioned spring clamps or arms 43 which project through the slot 7 and have the inner ends thereof secured to a flange or head 51 of a rotatable hollow stub shaft 52 into which the end of the supporting arm 40 projects. The shaft 52 is engaged in a supporting sleeve 44 which is integrally formed on the upper end of a lever or arm 45. The lower end of the lever 45 is pivotally supported on a pin or stub shaft 46 engaged in a bracket 47 secured on the base 48 of an 100 105 110 115 120 125 130

upright supporting frame 49. Connected to the lower portion of the pivoted lever 45 is one end of a control spring 50 the opposite or lower end of which is secured to the frame base 48 as clearly illustrated in Figure 2. Secured on the inner end of the stub shaft 52 is a gear 53. The gear 53 is in rolling mesh with an arcuate or curved rack 54 which is supported rigidly upon the frame 49. Adjustably projecting through one end of the rack 54 is a stop screw 55 the inner end of which is positioned in the path of travel of the pivoted lever or arm 45 to limit the swing thereof.

15 For the purpose of operating the pivoted lever 45 said lever has rotatably engaged on one side thereof a roller 56. The roller 56 has rolling contact with a control cam 57 which is secured on a cam shaft 58 journalled 20 in suitable bearings provided on the frame work 49.

As clearly illustrated in Figure 3 the cam shaft 58 projects into a gear box or housing 59 and has secured on the rear end thereof within the housing 59 a gear 60 which is in mesh with a driving pinion 61. The pinion 61 is secured on a stub shaft 62 which is also journalled in suitable bearings in the gear housing or box 59. Mounted on the 25 stub shaft 62 within the gear box 59 is a worm wheel 63 which is in mesh with a driving worm 64. The worm 64 is formed on a worm shaft 65 which projects from the gear box 59 and is connected with a motor driving shaft 66 by means of a coupling 67 as 30 illustrated in Figure 2. The motor shaft 66 forms part of a driving motor 68 which is mounted in the rear portion or chamber of the machine casing 1.

40 When the machine is operated by the motor 68 the control cam 57 will cause the pivoted lever 45 to swing back and forth from the full line position illustrated in Figure 2 into the full line position illustrated in Figure 5 causing the gripped fountain pen to be carried from a position over the filling cup or container 12 into a position over the discharge cup or container 13. As the lever 45 moves from the filling position to the 45 discharge position the gear 53 tracking over the rack 54 causes the fountain pen to be rotated through a complete revolution as indicated in the dotted line position of the fountain pen in Figure 1. The fountain pen is thus carried from one cup to the other for the purpose of drawing a supply of writing fluid from the cup 12 and then discharging the contents of the fountain pen barrel into the receiving cup 13.

60 The filling and discharge of the fountain pen is accomplished by operating the plunger mechanism 37 by mechanical means which will now be described. Pivots mounted on a stub shaft 69 supported on the upper 65 portion of the framework 49 is a rocker arm

or walking beam 70. Pivots connected to the walking beam 70 to one side of the pivot point thereof is the upper end of a connecting or operating rod 71 which slidably projects through a bracket arm 72 formed on the framework 49. The lower end of the connecting rod 71 is provided with a threaded shank or screw portion 73 having adjustably engaged thereon an adjusting nut 74 for the purpose of permitting a control coiled spring 75 to be adjusted. The coiled spring 75 is engaged around the connecting rod between the adjusting nut 74 and the bracket arm 72 as clearly illustrated in Figure 3. The spring 75 is provided for returning the walking beam to a normal position after the same has been operated. Engaged on the lower end of the connecting rod screw 73 is a forked bar or head 76 which slidably projects through a guide block 77 secured on the machine framework 49. Rotatably supported in the lower forked or recessed end of the guide block 76 is a roller 78 which is positioned to have rolling contact with the peripheral surface of a control cam 79 which is mounted on the cam shaft 58 for the purpose of governing the operation of the walking beam 70.

Integrally formed on one end of the walking beam 70 is a bearing sleeve 80 having journalled therein a plunger depressing rod or arm 81 which projects outwardly through the partition slot 8 and has the outer end thereof formed to afford a flattened depressing head 82 which at a predetermined time in the operation of the walking beam 70 is adapted to be brought into contact with the head of the fountain pen plunger 37 to slidably depress or move the plunger 37 inwardly from the full line position illustrated in Figure 4 into the completely depressed position illustrated in Figure 2 for the purpose of causing a charge of the writing fluid from the filling or supply cup 12 to be drawn upwardly through the fountain pen feed bar 110 into the transparent barrel 36 of the fountain pen to fill the same with a charge of writing fluid which is clearly visible through the transparent barrel 36. Secured on the inner projecting end of the plunger depressing rod or arm 81 is a passaged head 83 through which a guide wire or rod 84 slidably projects. The lower end of the guide rod 84 is pivotally connected in the lower end of the rack 54. The guide rod 84 slidably projects through the slotted head 83 of the plunger depressing arm 81 and serves to hold the head 82 of the depressing arm in substantially a right angled relation with the end of the head of the plunger 37 during a 120 depressing operation of the plunger.

Integrally formed on the upper or opposite end of the walking beam 70 is a passaged cylinder or bearing member 85. Rotatably engaged and projecting through the bearing 130

sleeve 85 is a fountain pen plunger actuating rod or arm 86 which projects outwardly through the partition slot 9 and has the outer end thereof shaped to provide an actuating hook 87 for engagement with the fountain pen plunger 37 beneath the head of the plunger for the purpose of causing the fountain pen plunger to be pulled outwardly from the depressed full line position of Figure 5 into the projecting dotted line position illustrated in said figure for the purpose of causing the charge of writing fluid in the fountain pen barrel 36 to be discharged outwardly through the writing end of the fountain pen into the liquid receiving container or cup 13 when the fountain pen is in a discharge position as illustrated in Figure 5. Secured on the inner projecting end of the plunger raising arm 86 is a passaged block 88. Slidably projecting through the block 88 is a wire or rod 89 the lower end of which is pivotally hooked in the upper end of the rack 54. The pivoted rod 89 projecting through the passaged block 88 of the plunger elevating arm 86 serves to hold the hook 87 in proper position for raising the plunger 37 when the walking beam 70 is operated. When the walking beam 70 is operated to move from the dotted line position of Figure 5 into the full line position the plunger raising hook 87 is so positioned that as the fountain pen is moved from the dotted line position of Figure 5 into the full line position the plunger 37 is moved into engagement with the hook 87 with the head of the plunger positioned above the hook to permit the plunger to be pulled outwardly to cause the contents of the fountain pen barrel to be discharged into the receiving cup 13, when the walking beam swings from the full line position of Figure 5 back into the dotted line position of said figure.

It will be noted that the demonstrating machine is so constructed that the transparent barrel plunger type fountain pen is adapted to be carried from a filling position over the feed cup 12 into a discharge position over the discharge cup 13 and that the fountain pen during its travel from one extreme position to the other is caused to rotate through a complete revolution to permit the plunger head to be properly positioned at predetermined times to be mechanically actuated by the depressing head 82 when the fountain pen is in a filling position and by the raising hook 87 when the fountain pen is in a discharge position. The machine is thus adapted to act automatically to clearly demonstrate the filling and discharging operations of the improved transparent barrel plunger type fountain pen.

For the purpose of describing the various steps in the operation of the fountain pen and for describing the novel features thereof of an illuminable visible movable sign mech-

anism is provided in the machine casing 1 behind the partition or panel 5 to permit various advertising and descriptive signs to be automatically moved in timed or synchronized relation with the operation of the demonstrating machine to cause appropriate descriptive signs to be moved into an observable position behind the sign opening 6 of the panel 5.

The advertising or sign mechanism comprises a frame 90 which is rigidly secured on the upper end of the framework 49 and is provided with a bearing sleeve 91 having a stub shaft 92 journaled therein. Secured on the inner projecting end of the stub shaft 92 is the hub plate 93 of an octagonal or multi-sided advertising or sign drum 94. Each of the plates or sides of the drum 94 has the outer surface thereof provided with a slogan or a descriptive clause or sentence which can be read through the panel opening 6 when a particular side of the drum is brought into registering position with said opening. The sign plates 95 are secured in position longitudinally on the exterior of the advertising or sign drum 94 and are preferably constructed of a translucent material to permit the same to be illuminated when desired by means of an electric light bulb 96 which is supported in a socket 97 secured to a frame arm 98.

The illuminating bulb 96 is positioned to project axially into the open end of the drum 94 as clearly illustrated in Figure 2.

For the purpose of rotating the advertising sign drum 94 in timed relation with the different steps in the filling and discharging operations of the fountain pen the drum hub plate 93 has secured on the outer end thereof a ratchet 99. For the purpose of operating the ratchet 99 a pawl arm 100 has one end thereof coacting with the ratchet teeth and the opposite end secured to the walking beam 70 to be operated thereby. The pawl arm 100 is so arranged that each time the plunger depressing end of the walking beam 70 is elevated the advertising or sign drum is rotated a predetermined amount to bring one of the signs in register with the panel opening 6. Connected to the pawl arm 100 is one end of a control spring 101 the opposite end of which is connected to one end of a pin or rod 102 supported by the walking beam and having the lower end of the pawl arm 100 engaged thereon.

For the purpose of more forcibly attracting the attention of an observer to the changing signs an audible mechanism is provided in the machine casing and comprises an electric bell 103 which is provided with an ordinary bell circuit having a control switch 104 connected in the circuit with the switch arm 105 having pivotally connected thereto one end of an operating link 106 the opposite end of which is pivotally connected to the pawl 130

arm 100 to be actuated thereby. It will thus be noted that each time the sign or descriptive matter is changed that the audible signal 103 will be operated. In case the audible signal is not desired the switch arm 105 may be disconnected from the pawl arm 100.

Attention is called to the fact that if desired an annunciator system such as a radio or phonograph set may be connected to be 10 operated in timed relation by the walking beam 70 for the purpose of explaining the various steps in the demonstration of the fountain pen operation.

The improved electrical advertising and 15 demonstrating machine has the mechanisms thereof enclosed in the casing 1 behind the demonstrating panel 5 which is provided with the slots 7, 8, and 9 through which the pen carrier or holder and the plunger actuating 20 members project. The panel 5 is also provided with the opening 6 through which the advertising and demonstrating signs may be viewed. Mounted in front of the panel 5 is the liquid supply cup 12 and the liquid 25 discharge or receiving cup 13 with the cup 13 positioned at a higher elevation than the cup 12 to permit liquid discharged thereinto to be returned by gravity through the pipe 14 to the cup 12. The glass front plate 3 30 of the casing is adapted to be removed through the top of the casing when the top moulding 4 is open so that the fountain pen holder or carrying bracket 39 may be removed from the sleeve 51 by simply swinging 35 the spring clamping arms 43 apart to release the holder 39 so that a fountain pen barrel may be engaged in position held by means of the clamps 41. For the purposes of demonstration the fountain pen cap is of course 40 removed and the head cap which normally encloses the projecting end of the plunger mechanism 37 is also removed from the fountain pen barrel. With the fountain pen barrel engaged in the clamping clips 41 the 45 screws 42 are tightened to tightly hold the fountain pen clamped in position. The arm or stem 40 of the holder 39 is projected through the slot 7 of the panel 5 and into the supporting sleeve 51 (Figure 3) until the 50 outer ends of the spring clamping arms 43 snap over the holder 39 to hold the holder and the fountain pen supported in position with the fountain pen positioned in front of the demonstrating panel 5.

55 To start the machine a control switch for the driving motor 68 is closed thereby causing the motor to drive the operating mechanisms by means of the gear members disposed in the gear box 59 to rotate the cam shaft 60 58 and the control cams 57 and 79 which are secured thereon. The control cam 57 coacting with the roller 56 causes the lever arm 45 to swing from the full line position of Figure 4 toward the full line position of Figure 5 65 causing the gear 53 to track over the rack

54. The movement of the lever 45 is adapted to carry the fountain pen back and forth from a filling position over the cup or container 12 into a discharging position over the discharge cup or container 13 with the gear 53 acting to cause the fountain pen to rotate through a complete revolution as indicated by the dotted lines in Figure 1 during the travel of the fountain pen from one extreme position to the other. The cam 57 acts to swing the lever 45 from the full line position of Figure 4 to the full line position of Figure 5 and is so constructed that the fountain pen is permitted to be held in a stationary position for a predetermined period of 80 time at the extreme positions of travel. After the charge of writing fluid has been emptied into the receiving cup or container 13 the control spring 50 acts to return the lever 45 to its normal position and thereby carry the 85 fountain pen back into the filling position.

The control cam 79 coacting with the roller 78 controls the operation of the walking beam or rocker arm 70 which is timed to operate in synchronized relation with the travel of the fountain pen so that when the fountain pen is returned to the filling position as illustrated in Figure 4 the plunger 37 is in its outermost or extended position and the fountain pen barrel is empty. When the fountain pen is in a position to be filled the head of the plunger 37 is brought in position beneath the depressing head 82 and with the operation of the walking beam from the full line position of Figure 4 into the dotted line position the depressing head 82 pushes downwardly on the plunger 37 thereby projecting the plunger into the fountain pen barrel 36 to cause a charge of writing fluid from the filling cup 12 to be drawn upwardly through the fountain pen feed bar into the ink chamber of the fountain pen barrel to fill said chamber as illustrated in Figure 2. The type of fountain pen adapted to be demonstrated by the machine of this invention is of the type disclosed in my pending application for patent for a "fountain pen" filed April 24th, 1930, U. S. Serial No. 446,807.

115 After the filling of the fountain pen barrel the control cam 79 acts on the walking beam 70 to cause the depressing head 82 to be elevated as the fountain pen is carried by the pivoted lever 45 from the full line position illustrated in Figure 4 toward the 120 full line position illustrated in Figure 5 causing the fountain pen to be revolved through a complete revolution whereby the fountain pen as it approaches its extreme position of travel toward a discharge position the plunger head 37 is moved into engagement with the plunger elevating hook 87 while the fountain pen is temporarily held stationary in the discharge position illustrated in Figure 5 ready to have the contents of the foun- 125 130

tain pen barrel discharged. At this point in the operation the control cam 79 again acts on the walking beam 70 to cause the same to swing from the full line position of Figure 5 into the dotted line position thereby causing the hook member to be raised to draw the fountain pen plunger 37 upwardly causing the liquid contents of the barrel 36 to be discharged into the discharge or receiving container or cup 13.

The sign carrying drum 94 which is mounted in the casing behind the opening 6 of the demonstrating panel 5 is illuminated by the electric bulb 96 and is rotated a predetermined amount each time the plunger depressing end of the walking beam 70 is moved from the dotted line position of Figure 4 toward the full line position. The upward swing of the walking beam causes the pawl arm 100 to coact with the ratched 99 to cause the sign drum to be rotated a predetermined amount to cause an appropriate sign to be moved into register with the panel opening 6 to be viewed from the front of the demonstrating cabinet. In case it is desired to more forcibly call the attention of observers to the signs an audible signal of any desired type such as the bell 103 may be operated each time the sign is changed by means 30 of the connecting link 106 which connects the pawl arm 100 with the switch blade or arm 105 of the bell control switch 104.

By means of the reserve liquid supply bottle or tank 21 the demonstrating liquid in the filling container or cup 12 is adapted to be replenished as required to compensate for evaporation of the liquid, leakage or other causes.

It will of course be understood that various details of construction may be varied through a wide range without departing from the principles of this invention and it is therefore not the purpose to limit the patent granted hereon otherwise than necessitated by the scope of the appended claims.

I claim as my invention:

1. An electric advertising and demonstrating machine comprising a display cabinet, a slotted panel therein, a liquid supply cup and a liquid receiving cup mounted in front of said panel, a holder disposed in front of said panel and projecting through one of the slots thereof, a transparent barrel plunger type fountain pen supported by said holder, means in said cabinet for supporting said holder and carrying the same back and forth between said liquid supply cup and said liquid discharge cup, a control member in said cabinet means for operating the same, and plunger operating mechanisms carried by said control member and projecting outwardly through slots of said panel and adapted to engage the fountain pen plunger to actuate the same when the fountain pen is positioned above said supply cup to cause a charge of

liquid to be drawn from the supply cup into the fountain pen barrel and also cause the charge of liquid to be discharged from the fountain pen barrel into the discharge cup when the fountain pen is positioned over the discharge cup.

2. A fountain pen demonstrating machine comprising a cabinet, a slotted panel therein, a liquid supply cup and a liquid receiving cup mounted in front of said panel, means for carrying a transparent barrel plunger type fountain pen back and forth between said cups and means for operating the fountain pen plunger to cause a charge of liquid to be drawn from the supply cup into the fountain pen barrel and then cause the contents of the fountain pen barrel to be discharged into the receiving cup.

3. A fountain pen demonstrating machine comprising a cabinet, means for carrying a transparent barrel plunger type fountain pen through a predetermined path in front of the cabinet, and mechanisms coacting with the fountain pen plunger at predetermined positions in the path of travel of the fountain pen to cause the plunger to be pushed into the fountain pen barrel in one position and furthermore cause the plunger to be withdrawn from the fountain pen barrel in another position.

4. A fountain pen demonstrating machine comprising a cabinet, a fountain pen holder, means for carrying the same through a predetermined path, a transparent barrel plunger type fountain pen engaged in said holder to be carried thereby, a plunger depressing mechanism, a plunger elevating mechanism, and means for actuating said plunger depressing mechanism to engage and depress the fountain pen plunger in one position of travel of the fountain pen to cause filling of the fountain pen, said means also adapted to operate the plunger elevating mechanism to cause the same to engage and pull the fountain pen plunger outwardly in another position of travel of the fountain pen to empty the fountain pen.

5. The combination with a transparent barrel plunger type fountain pen, of means for carrying the same through a predetermined path, plunger actuating mechanisms positioned along the path of travel of the fountain pen and means for operating the plunger actuating mechanisms at predetermined times to cause alternate filling and emptying of the fountain pen.

6. The combination with a plunger type fountain pen, of a holder for gripping and carrying the fountain pen through a predetermined course, means for carrying and operating the holder to cause the fountain pen to be carried from a filling position into a discharge position, a movably supported member, plunger actuating mechanisms on said member for engaging and operating the

fountain pen plunger when the fountain pen is in the filling and emptying positions, an advertising mechanism, and means for operating the advertising mechanism, said means being operable by the member to cause the advertising mechanism to operate in synchronized relation with the operations of the fountain pen.

7. The combination with a plunger type fountain pen, of means for carrying the fountain pen through a predetermined path, mechanisms for operating the fountain pen plunger to alternately cause filling and emptying of the fountain pen, and driving means for operating the carrying means and said operating mechanism in timed relation.

8. In an electric advertising and demonstrating machine the combination with a fluid feed cup and a fluid receiving cup, of a plunger type fountain pen, a traveling holder for gripping the fountain pen and carrying the same back and forth between the feed cup and said receiving cup, an actuating mechanism adapted to coact with the fountain pen plunger when the fountain pen is over the feed cup and over the receiving cup to cause the fountain pen to be alternately filled and emptied, control members for governing the operation of said holder and said operating mechanism, and a driving means for operating the control members.

9. In an advertising and demonstrating machine of the class described the combination with a plunger type fountain pen, of a liquid supply cup, and a liquid receiving cup, means for connecting said cups, means connected with the liquid supply cup for replenishing the supply of liquid therein when necessary, a holder for the fountain pen, a pivotal support for the holder, means for operating the pivotal support to carry the fountain pen back and forth between the liquid supply cup and the liquid receiving cup, a pivoted walking beam member, a plunger actuating mechanism carried on each end of said walking beam member, and control means for operating the walking beam member to cause the plunger actuating mechanisms to automatically operate the fountain pen plunger when the fountain pen is over the liquid supply cup and over the liquid discharge cup to cause a charge of liquid from the liquid supply cup to be drawn into the fountain pen and then be discharged into the receiving cup.

10. In a fountain pen demonstrating machine the combination with a plurality of liquid cups, of a plunger type fountain pen, means for carrying the fountain pen back and forth between said cups and temporarily holding the fountain pen in a stationary position when over said cups, a plurality of mechanisms for actuating the fountain pen plunger when over said cups to cause a supply of liquid to be drawn into the fountain

pen from one of said cups and then cause the charge of liquid to be discharged into another of said cups and means for controlling the operation of said plunger actuating mechanisms in timed relation with the operation of the fountain pen holder.

11. The combination with a plunger type fountain pen and a traveling holder therefor, of a liquid supply cup and a liquid receiving cup spaced from one another, means for carrying the fountain pen holder and the fountain pen back and forth between said cups, reciprocating members for engaging and operating the fountain pen plunger when over said cups to cause a charge of liquid to be drawn from the supply cup when the fountain pen is over said cup and furthermore cause the supply of liquid in the fountain pen to be discharged into the receiving cup when the fountain pen is over said cup, a pivoted support for said reciprocating members, control mechanisms for governing the operation of the traveling holder and said support, and a common drive for said control mechanisms.

12. A fountain pen demonstrating machine comprising in combination a holder, a plunger type fountain pen engaged therein, a liquid supply cup, a liquid receiving cup spaced therefrom, means connecting said liquid receiving cup with said liquid supply cup to return liquid thereto, a liquid replenishing unit connected with the liquid supply cup, a pivoted lever carrying said holder, means for operating said lever to cause the fountain pen to be carried back and forth between said cups, a pivoted walking beam, a plunger actuating mechanism on each end of said walking beam, means for operating the walking beam to cause the plunger actuating mechanism to cause the fountain pen plunger to be alternately pushed into the fountain pen and pulled outwardly therefrom to cause filling of the fountain pen when the same is positioned over the supply cup and to cause emptying of said fountain pen when the fountain pen is positioned over the receiving cup, cam means for governing the operation of said lever and said walking beam and a common driving means for operating said cam means.

13. A demonstrating machine comprising in combination with a plunger type fountain pen, a holder for the fountain pen, a liquid supply cup, a liquid receiving cup spaced therefrom, a pivoted lever for supporting said holder, a stationary rack, a gear on said holder meshing with said rack, a roller carried by said lever, a control cam coacting with said roller, a return spring connected with said lever, a cam shaft for supporting said cam, means for driving the cam shaft to cause the cam to coact with the roller to operate said lever to cause the fountain pen to be carried from a position over the filling cup

- into a position over the receiving cup, a pivoted walking beam, a plunger operating member supported on each end of said walking beam, a spring controlled member for 5 operating the walking beam to cause the plunger operating members to push the plunger into the fountain pen when the fountain pen is positioned over the filling cup to cause filling of the fountain pen and further- 10 more cause the fountain pen plunger to be drawn outwardly when the fountain pen is positioned over the receiving cup to cause the contents of the fountain pen to be discharged into the receiving cup, a spring controlled 15 mechanism for operating the walking beam, a roller carried by said spring controlled mechanism, and a cam coacting with said roller, said cam being mounted on the cam shaft.
- 20 14. In a fountain pen demonstrating machine of the class described the combination with a holder for carrying a plunger type fountain pen, of a pivoted member, driving means for operating said member, plunger operating devices carried by said member and said means for rotating the holder and carrying the same through a predetermined path to cause the fountain pen to be alternately brought into the field of operation of said 25 plunger actuating devices to cause reciprocation of the plunger by said devices to alternately fill and empty the fountain pen.
- 30 15. In a demonstrating machine the combination with a plunger type fountain pen, of a holder therefor, means for rotating the holder and carrying the same through a predetermined path, a liquid feed cup at one end of said path, a liquid receiving cup at the opposite end of said path, a pivoted member, means for operating the same, plunger actuating devices carried by said member to cause the fountain pen plunger to be depressed when the fountain pen is positioned over the feed cup to cause the fountain pen 35 to be filled and adapted to cause depression of the plunger into the fountain pen when the fountain pen is over the receiving cup to cause emptying of the fountain pen into said receiving cup, and a common drive for actuating the operating means for the holder and said member.
- 40 16. A demonstrating machine comprising a holder, for carrying a plunger type article to be demonstrated, of means for carrying the holder back and forth through a predetermined path, a mechanism for rotating the holder during the travel thereof, and mechanisms for actuating the plunger of said article when the article is positioned at the ends 45 of the path of travel thereof.
- 45 17. In a demonstrating machine of the class described the combination with a pair of liquid cups, of a holder for carrying a chambered article, means for carrying the holder and article back and forth between 50 said cups and holding the article stationary when over said cups, and mechanisms for operating the article when the same is held stationary over said cups to cause the article to be alternately filled when over one of said 55 cups and emptied when over the other of said cups.
- 55 18. In a demonstrating machine of the class described the combination with a pair of containers, of means for maintaining a predetermined supply of liquid in said containers, of a mechanism for carrying a chambered article to be demonstrated alternately from one of said containers to the other, means for operating the article when over one of said containers to cause the article to be filled with a liquid, a second means for actuating the article when over the other container to cause the article to be emptied, a common actuating mechanism for simultaneously operating the filling means and the emptying means, and a common driving means for operating the common actuating mechanism and said article carrying mechanism.
- 60 19. In a plunger type fountain pen demonstrating machine the combination with a liquid supply cup, of a liquid receiving cup, means for carrying a plunger type fountain pen back and forth between said cups, and a mechanism for automatically operating the fountain pen plunger when the fountain pen is positioned over said cups to alternately cause filling and emptying of the fountain pen.
- 65 20. In a plunger type fountain pen demonstrating machine of the class described the combination with a pair of cups, connected with one another, means for maintaining a predetermined supply of liquid in said cups, a cam controlled mechanism for carrying a plunger type fountain pen back and forth between said cups, and means for operating the fountain pen plunger when the fountain pen is positioned over said cups.
- 70 21. An article demonstrating machine comprising a pivoted lever, means for pivotally swinging the same, an article holder rotatably supported on said lever, means on said holder for removably clamping an operative article in position, a stationary rack, a gear on said holder meshing with said rack to cause rotation of the holder when the lever is operated, a pivoted walking beam, operating members carried by the walking beam for operating the article carried by said holder, means for operating the walking beam, and a driving device connected to operate the lever swinging means and the walking beam operating means.
- 75 22. An article demonstrating machine comprising a pivoted lever, a roller rotatably mounted thereon, a cam coacting with said roller for pivotally swinging the lever, a spring connected with said lever for return-

ing the same to normal position, a cam shaft for supporting said cam, means for driving the cam shaft, a holder rotatably supported on said lever for carrying an operative chambered article, a stationary rack, a gear on said holder coacting with said stationary rack to cause rotation of the holder and the article when the lever is operated, a pivoted walking beam, a spring controlled member for operating the same, a roller carried by said spring controlled member, a control cam on said cam shaft coacting with said roller, article operating members rotatably supported on said walking beam, control members pivotally connected to the stationary rack and having sliding engagement with said operating members for properly positioning the same when the walking beam is operated, said operating members adapted to engage the article carried by said holder at predetermined positions in the path of travel of the article to operate the article for demonstrating the same.

23. A demonstrating machine for an article having operative parts, said machine comprising a movable and rotatable carrier for said article, a movable operating mechanism, a control shaft, means for driving the same, control means on said shaft coacting with the carrier and with the operating mechanism to actuate the same to cause the article to be rotated and carried through a predetermined path to have the operative parts thereof operated by the operating mechanism in predetermined positions in the path of travel of the article, and auxiliary means operable by the operating mechanism to assist in the demonstration of the article.

24. A demonstrating machine for an article having a slidable member forming a part thereof, a pivoted member, a pushing device supported on one end thereof, a pulling device supported on the opposite end thereof, means for actuating the pivoted member, and an article carrying mechanism for alternately carrying an article into the fields of operation of the pushing device and the pulling device to cause the slidable member of the article to be reciprocated to demonstrate the article.

In testimony whereof I have hereunto subscribed my name at Chicago, Cook County, Illinois.

SOLOMON M. SAGER.
